Augustin Frey by Alidney Bram altq

UNITED STATES PATENT OFFICE.

AUGUSTUS FREY, OF NEW YORK, N. Y.

DESIGN FOR CIGAR-BOXES.

Specification forming part of Design No. **11,436**, dated September 30, 1879; application filed August 4, 1879.
[Term of patent 7 years.]

To all whom it may concern:

Be it known that I, AUGUSTUS FREY, of the city, county, and State of New York, have invented and originated a new and original Design for a Receptacle for Cigars, Cigarettes, and Tobacco, of which the following is a specification, reference being had to the accompanying drawings, and to the letters of reference marked thereon, in which—

Figure 1 is a view showing the receptacle A. Fig. 2 is a view of the same when placed within a suitable frame-work. Fig. 3 is a transverse vertical section of the same.

In the drawings like parts of the invention are designated by the same letters of reference.

The nature of my invention consists in a design for a receptacle for cigars, cigarettes, and tobacco, as more fully set forth.

In the drawings, A is the receptacle for

cigars, cigarettes, and tobacco. This receptacle A, usually formed of glass, has its lower side, B, formed flat, a flat mouth or opening at the top to allow access to the receptacle, and its ends D¹ and D² made convex, as shown.

E is a suitable frame-work, within which the receptacle A is received, and F is a cover, placed over the opening in the upper side of the same.

Having now described my invention, what I claim as new, and desire to secure by Letters Patent, is—

A design for a receptacle, consisting of the flat bottom B, vertical sides F', convex ends D¹ D², the sides and ends terminating at a horizontal mouth, as shown.

AUGUSTUS FREY.

In presence of—

A. SIDNEY DOANE,
WILLIAM V. H. HICKS.
